(57) **CLAIM**

The ornamental design for a cordless telephone, as shown and described.

DESCRIPTION

FIG. 1 is a perspective view of a handset inserted into a full featured base station.

FIG. 2 is a perspective view of the full featured base station of FIG. 1.

FIG. 3 is a perspective view of the handset of FIG. 1; and, FIG. 4 is a side detail view of the handset of FIG. 1.

The full featured base station and handset are shown separately in FIGS. 2 and 3 for the convenience of illustration.
